(57) **CLAIM**

The ornamental design for a module for storage rack for compact discs, cassettes, and the like, as shown and described.

DESCRIPTION

FIG. 1 is a perspective view of the front right side of the module for storage rack for compact discs, cassettes, and the like showing a first embodiment of my new ornamental design;

FIG. 2 is a perspective view of the rear left side thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a perspective view of the front right side of a second embodiment of my new ornamental design, illustrating two modules in a stacked or vertical arrangement thereof; and,

FIG. 10 is a perspective view of the front left side of a third embodiment of my new ornamental design, illustrating two modules in a side-by-side or horizontal arrangement thereof.
